(57) **CLAIM**

The ornamental design for an electronic camera, as shown and described.

DESCRIPTION

FIG. 1 is a top, front and right side perspective view of an electronic camera showing my new design;

FIG. 2 is a front elevational view thereof;

FIG. 3 is a rear elevational view thereof;

FIG. 4 is a top plan view thereof;

FIG. 5 is a left side elevational view thereof; and,

FIG. 6 is a right side elevational view thereof.

The material shown in broken line illustrates the environment of the present invention.
